STIRRUP

Edward E. Armentrout, Dupree, S. Dak.

Application January 18, 1932, Serial No. 587,407
Renewed March 23, 1934

4 Claims. (Cl. 54—48)

My invention relates to a new and novel saddle stirrup and the like, and to a new and novel method of constructing the same.

It is an object of my invention to provide a stirrup which can be attached to any type of saddle or the like, which is flexible and elastic, and which is composed almost entirely of rubber.

It is also an important object of my invention to construct a stirrup of the type described from 10 old pneumatic tires.

It is also an important object of my invention to provide a simple and inexpensive method of constructing a stirrup of the type described, chiefly from old pneumatic tires.

15 Other objects and advantages of my invention will be apparent from a reading of the following description of the drawing, wherein for purposes of illustration a preferred embodiment of the invention is shown.

20 In the drawing:—

Figure 1 is a side elevational view of a preferred embodiment of my invention.

Figure 2 is a transverse vertical sectional view through Figure 1.

25 Referring in detail to the drawing the numeral 5 refers generally to the stirrup which is formed of an outer layer of fabric 6 and an inner layer or layers of rubber 7. The body made up by the layers 6 and 7 may be increased in thickness by 30 the use of several of such layers.

A narrower layer of fabric 8 supports a block of rubber 9.

The layers 6 and 7 are of elongated form and their ends are brought upwardly in inwardly 35 pending manner as shown in Figure 1 to form an open U-shaped form, following the general contour of a conventional metal stirrup.

40 A hang bolt 10 is placed through apertures in the upper end portions of the side members of the stirrup, and a rubber tubular spacer 11 is circumsposed upon the hang bolt 10 so as to preserve the proper spacing of the upper portions 45 of the side members of the stirrups.

45 As will be observed in the drawing, the rubber block 9 is of thick heavy character provided with tapered end portions 11, 11 so that an attractive, convenient merging will be achieved with the adjacent surfaces at the terminations of the block 9. The upper surface of the block and the corners thereof are rounded so as to properly 50 seat the foot of the rider. If desired other holes 12 may be made in the side members of the stirrup to accommodate different heights of the hang bolt and spacer 10, 11.

55 It will be observed that the stirrup of my in-

vention has, among other advantages, the following:—It is comfortable, silent when striking other parts of the saddle or equipment, and being flexible and elastic, eliminates jolts and shocks at every gait of the animal ridden, and the soft 5 yielding material and the character of the block 9 permits the rider to flex his feet while riding, which is very advantageous and conducive to comfort especially in cold weather, when the feet have a tendency to be disagreeably affected by 10 the cold; and the use of the stirrup of my invention gives the rider poise and a sense of security. In case of a fall the foot being encased in yielding material instead of in metal, will be 15 preserved against injury, which would otherwise occur.

The method of constructing the stirrup of my invention is as follows:—

I take an old tire of the pneumatic type, and 20 make transverse cuts therein so as to separate therefrom an elongated plate composed of the rubber treads, the rubber side walls, and the underlying fabric structure, the plate being tapered toward each end in the shape indicated in the drawing. I then form in the end portions holes 25 12 for receiving the hang bolt. I then form and attach the heavy rubber block 9 intermediate the ends of the plate on the rubber side thereof and attach the same in this position securely. I then bring the ends of the plate upwardly, with the 30 fabric structure on the outside, pass the hang bolt through one of the holes in the plate, place the spacer 11 on the bolt, then pass the bolt into one of the holes of the remaining sides of the 35 stirrup and attach the nut 13 so as to retain the described parts assembled as shown. If preferred, the foot engaging surface of the block 9 may be corrugated or otherwise roughened so as to increase the frictional engagement therewith with 40 the foot of the rider, though the form shown is adequate to the purposes of the invention. It will be obvious that the device of my invention can be constructed at a much lower cost than any correspondingly serviceable device of this 45 character.

While I have shown and described a preferred embodiment of the structure and method of the invention, it is to be understood that I do not desire to limit the application of the invention 50 beyond the scope of the subjoined claims.

What is claimed is:—

1. A stirrup comprising a plate of pliant and 55 resilient material bent into U-form, the ends of the legs of the U-form having connecting them a hang bolt and spacer, a body of compressible ma-

- terial secured within and upon the bight portion of the U-form.
2. A stirrup comprising a plate of resilient pliant material bent into U-form and provided with a hang bolt and a spacer between the ends of the legs of the U-form, a body of compressible material secured within and upon the bight portion of the U-form, said plate being constructed of a plate of resilient pliant material reinforced on its outward side with a plate of fabric material.
3. A method of making a stirrup, comprising, cutting a tire casing transversely to provide a plate of elongated form, then attaching at a central portion of the tread side of the plate a merging block of resilient material to be engaged by the foot of the rider, then bending the ends of the plate upwardly toward each other into a U-form with the inner fabric side of the tire casing outward, a hang bolt being then secured through holes formed in the ends of the plate with a tubular spacer on the bolt between the ends of the plate.
4. A stirrup comprising an elongated plate transversely cut from a pneumatic tire casing having one side fabric and the other rubber, the ends of the plate being reversely bent so as to form the plate into a U-shape with the fabric side of the plate outward, the ends being connected by hang bolt and spacer means.
